UNITED STATES PATENT OFFICE.

JOHN H. MOLINELLI, OF WEST PITTSSTON, PENNSYLVANIA.

SURGICAL INSTRUMENT.

Application filed March 10, 1925. Serial No. 14,857.

To all whom it may concern:

Be it known that I, JOHN H. MOLINELLI, a citizen of the United States, residing in West Pittston, in the county of Luzerne in the State of Pennsylvania, have invented certain new and useful Improvements in Surgical Instruments, of which the following is a full, clear, and exact disclosure.

My invention relates to surgical instruments and more particularly to obstetrical instruments, and has for its particular object the prevention of injury and especially the rupture of the perineum during the process of parturition.

15 A further object of my invention is to provide an instrument of thin soft metal which is strong and has tensile strength, but is easily bent to any desired shape and which will automatically be bent and shape itself 20 while in use to conform to the presentation and to the perineum.

A further object of my invention is to provide a metal instrument which by reason of its pliability and flexibility, and lack of 25 resiliency will distribute the pressure between the foetus and the soft parts of the perineum over substantially all of the posterior or recto-perineum so that the liability of rupturing the perineum is greatly reduced.

30 A further object of my invention is to provide an instrument, of the character above described, of thin smooth soft pliable non-resilient metal, which will shape itself 35 to the head or other presentation of the infant being delivered and protect the perineum, without injuring the said head or other part of the presentation.

40 A further object of my invention is to provide an instrument of the character above described, with a thin flat shank or handle which is also of the same and integral with the soft pliable non-resilient metal of the operating part thereof, so that the handle 45 may be readily bent and fitted to the hand and fingers of the surgeon, thus making the handle practically adjustable to conditions which vary in every individual case, and to 50 make the main or body portion of the instrument equally adjustable to the different varying conditions found in cases of this character.

55 Other objects of my invention will appear in the specification and claims below.

Referring now to the drawing forming a part of this specification and in which the

same reference characters are employed throughout the various views to designate the same parts,

Fig. 1 is a plan view of one embodiment 60 of my invention.

Fig. 2 is a side elevational view of the same.

Fig. 3 is a cross-sectional view on the line 3—3 of Fig. 1.

65 Fig. 4 is a longitudinal axial sectional view of the same after the handle has been bent to fit the fingers of the surgeon and showing how the thumb of the surgeon is free to apply pressure thereto to evenly 70 press against and stretch the soft parts of the perineum; and

Fig. 5 is a view similar to Fig. 4 but showing how the operating part of the instrument may be further slightly bent by the 75 surgeon longitudinally if found desirable.

In the form of my invention shown in the drawing, the instrument when substantially straight as in Fig. 1, is preferably about eight or nine inches long and a little less 80 than two inches wide in its widest part 1, the narrower half 2 being arranged to be bent into a handle 2 as will be referred to below.

The larger or operating portion 1 is preferably slightly concaved transversely as shown in Figs. 1 and 2 while the handle portion 2 may be and preferably is at first straight and flat.

85 The forward edge is provided with smooth 90 rounded corners 3, 3 and the corners 4, 4 where the width is decreased to form the handle 2 are similarly smooth and tapering.

The instrument is preferably originally 95 stamped out of a relatively thin sheet of German silver and then the entire edge is smoothed and rounded as clearly indicated at 5 in Figs. 2 and 3 so that there will be no sharp edges or corners or angles anywhere around the margin thereof.

100 When the surgeon finds it desirable to use the instrument he first manually shapes the operating portion 1 by curving it transversely to an arc conforming to the general transverse shape of the inner surface of the perineum of the patient and he may bend it slightly longitudinally if he finds it necessary or desirable in a particular case. He then bends the handle into a more or less 105 S-shape, that is he reversely curves it longitudinally as shown in Figs. 4 and 5 to form the upper loop or bend 6 and the lower 110

loop 7 conforming to the shape, slant and size of the fingers of the surgeon. This forms a handle which gives the surgeon a very firm and secure grip on the instrument insuring perfect and certain control of it for he may insert the index finger 8 and the finger 10, second removed from the index finger 8, in the upper curved portion 6 of the handle and the middle finger 9 (the one next the index finger 8) in the lower bend 7, leaving the thumb 11 free to be used to press on the concave upper surface of the operating portion 1 without destroying his firm hold on the handle of the instrument. Having thus quickly shaped the instrument and properly lubricated it, with the fingers aforesaid in the loops 6 and 7 and the thumb 11 above or a little in advance of the index finger 8, the surgeon can easily and with certainty introduce the curved operative portion of the instrument, between labor pains, into the vagina, posteriorly over the perineum. The thumb 11 of the surgeon is now free to be moved longitudinally of the concave portion 1 to substantially any position to apply pressure to any part thereof and to further shape the portion more perfectly to the perineum and to stretch the same as may be found necessary, without releasing his firm grip on the handle portion 2. As the foetus advances and the head or other presentation reaches the perineum, the thin German silver operating portion 1 distributes the pressure over the entire recto-perineum and greatly reduced the liability to rupture or tearing of the perineum and at the same time the head or other presentation may further bend the instrument to conform more perfectly to the shape of the head.

The foetus in advancing slips or slides over the lubricated operating portion 1 without injury to the head or other presentation or to the perineum.

Moreover, the instrument can be withdrawn if desired before complete delivery without injury to the mother or child as the surfaces are all smooth, the edges are dull and the whole instrument is preferably well lubricated.

After having been used the instrument may be cleaned, sterilized and bent back to flat shape for convenient packing and transportation.

The device is clearly distinguished from that class of instruments which are rigid and unbending, which are inserted anteriorly into the mouth of the uterus to deflect the head of the foetus posteriorly off the pubic arch, for said class of devices are used as levers, to pry, move and direct the foetus, whereas both the operating part and handle of my device are not rigid but are pliable, freely bendable and non-resilient and cannot be used as a pry or lever. My instru-

ment substantially forms a metal cover, protector or strengthener extending over the recto-perineum to strengthen the same, to distribute the pressure and to prevent the tearing and rupture of the perineum during 70 parturition.

Thus I have provided an instrument for the purposes above described in which the main or operating portion may be readily bent transversely into arcuate or cylindrical 75 form of any desired radius, and can be longitudinally manually curved slightly as occasion may require, and which is of soft pliable non-resilient metal formed with a continuous rounded marginal edge and without any sharp angular edges or corners, the corners being provided with smooth slow curves which will not scratch, cut or scrape the delicate surface on which it is adapted 80 to be used.

Since the normally flat handle is made of the same flexible non-resilient material as the operating portion, it may readily be so bent and fitted around and between the fingers of the user as to insure a firm and sure grip on the instrument when in use notwithstanding the fact that the instrument may be completely covered by and with a suitable lubricant. The instrument so lubricated will not slip or change its position 95 with respect to the hand of the surgeon even when the thumb and possibly the index finger also may be temporarily employed for other purposes than grasping the handle of the instrument.

Although I have illustrated and described one way in which the handle may be bent in and around the fingers of the user, it is evident that it would probably seldom be bent twice to exactly the same shape, and that different operators might bend it in some other way to insure a firm grip on the instrument under different conditions and such changes are fully within the aim and scope of the present invention. The operating portion may also be made in different sizes and in slightly varying details and be within the spirit of my invention.

While I have found that German silver is a metal which is well adapted to the purposes of this instrument, I do not wish to be construed as limited strictly to the use of this metal therein, since other non-corrosive alloys and materials, having the requisite strength, combined with ready pliability and non-resiliency, and capable of receiving and retaining a smooth polished surface may be employed without departing from the aim and scope of my invention as defined in the appended claims.

Having thus described my invention, what I claim and desire to protect by Letters Patent of the United States is:

1. An obstetrical instrument made entirely of thin flexible non-resilient sheet metal 130

- and comprising an elongated nearly flat operating portion readily manually bent and shaped transversely into an arcuate or cylindrical form, and a normally flat handle freely bendable to conform to the shape, size and position of the fingers of any user, said instrument being provided with a continuous smooth rounded dull marginal edge free from corners or sharp angles.
- 5 2. An obstetrical instrument having an elongated nearly flat operating portion readily manually bent and shaped transversely into an arcuate or cylindrical form, and a handle integral therewith, said instrument being composed throughout of non-resilient sheet metal, said operating portion being thin and flexible enough to be automatically bent by the pressure between the presentation and the perineum to conform to the shape of the presentation and of a size to distribute the pressure substantially evenly over the perineum.
- 10 3. An obstetrical instrument having an elongated operating portion readily manually bent and shaped transversely into an arcuate or cylindrical form, and a handle integral therewith, said instrument being composed throughout of non-resilient sheet metal and having an operating portion, thin and flexible enough to be automatically shaped by the pressure between the presentation and the perineum, to conform to the shape of the presentation and of the perineum and of a size to distribute the pressure substantially evenly over the perineum.
- 15 4. An obstetrical instrument having an elongated operating portion curved transversely and also slightly curved longitudinally to provide a concave upper surface and a convex under surface, and a handle integral therewith, said instrument being composed throughout of non-resilient sheet metal, said operating portion being thin and flexible enough to be automatically bent by the pressure between the presentation and the perineum to conform to the shape of the presentation and of the perineum and of a size to distribute the pressure substantially evenly over the perineum.
- 20 5. An obstetrical instrument having a handle and a smooth operating portion of thin flexible non-resilient sheet metal of substantially the size and of the shape in general of the inner surface of an extended and stretched perineum, and adapted to be placed between the presentation and the perineum to strengthen, to protect and to distribute pressure over the perineum, during parturition to prevent rupture of the perineum.
- 25 6. An obstetrical instrument having an operating portion and a handle of normally flat thin, flexible non-resilient sheet material adapted to be readily bent and wrapped around and between the fingers of any user to prevent the slipping of the instrument with respect to the hand of the operator while being used.
- 30 In testimony whereof, I have hereunto set my hand this sixth day of March, 1925.
- 35

JOHN H. MOLINELLI.
